ALARM DEVICE

Charles L. Eads, Los Angeles, Calif.

Application June 30, 1950, Serial No. 171,478

9 Claims. (Cl. 116—75)

1

This invention belongs to that general class of devices known as alarms for use on doors, windows, etc., wherever protection is desired. A glass breaking means is provided for emergency use of the lock and for setting-off the alarm, and key means are provided for unlocking the door or window without setting-off the alarm. The alarm means, when once started, may be continuous or intermittent in operation with high or low volume depending upon the particular place where the invention is employed. Soundless indicating means, such as lights and moving signals may be combined with the invention and electrical and mechanical connections made to warn a watchman or guard at some remote point.

The invention has among its objects the production of a means of the kind described and claimed that is simple, durable and compact in structure, inexpensive to make and manufacture, dependable and efficient in use and service, convenient to handle and install, and pleasing and attractive in appearance and very satisfactory for use whenever and wherever found applicable.

Other objects, advantages and features of this particular invention will appear from a careful perusal of the accompanying drawings, the subjoined detailed description, the preamble of these specifications, and the claims appended hereto.

Below, applicant describes one of the preferable forms of his invention in order to teach the art thereof, and show how to make and use the same, but it is to be understood that the drawings and description thereof are not to limit the invention in any sense whatsoever except as the same may be limited by the prior art. Language employed herein is not to be construed as giving any unauthorized person or organization the right to make, use and/or sell the invention herein disclosed.

In the drawings:

Figure 1 is an elevational view of a portion of one side of a typical door with the combination alarm and lock device installed thereon;

Figure 2 is an elevational view, partly in section, cover removed, enlarged, showing the working parts;

Figure 3 is a vertical sectional view taken substantially along the line 3—3 of Fig. 2;

Figure 4 is a partial plan view showing a detailed part and taken along the line 4—4 of Fig. 3;

Figure 5 is a sectional view taken along the line 5—5 of Fig. 2;

2

Figure 6 is an elevational view of some parts;

Figure 7 is a perspective view of some bell parts;

Figure 8 is a perspective view of a detailed part;

Figure 9 is a section taken along line 9—9 of Figure 2.

The particular device, as illustrated, employs a wind-style mechanical bell protected by a suitable casing against damage and tinkering so that the fire door or other type of emergency door or opening will be in a foolproof order at all times. Unless such an emergency exit or entrance lock can be depended upon at all times to give care-free service, there would be no real advantage in their placement.

As shown in the drawings, the reference character 1 indicates an emergency exit door which has vertically arranged hinges along its edge 2 so that the edge 3 is shiftable to and from the door jamb 4. The lock keeper is indicated at 4', and held in fixed position by screws or other means.

The alarm mechanism is mounted upon a base 5 which has suitable means, such as screws or bolts for securing it to the door 1; the screws passing through holes in the base. The well known bolt or tongue 6 rides between the spaced guides 8 and 7 and the bolt has the rod 9 fixed thereto which slides through a suitable opening of the guide member 10; a spring 11 being coiled around the rod to constantly urge the bolt outwardly toward the keeper. It may be well to state here, that any suitable keeper may be employed with the invention, but it is preferred to use one having the heavy protection flange like the one indicated at 4''.

The bolt rod has the stop plate 13 fixed thereto which can ride within certain limits, that is, between the guide 10 and the catch element 14. In order to move the bolt without disturbing the catch 14, a cam arm 15 is employed and this arm 15 is securely fixed to the lock stem 16, and this stem extends from the well known type of cylinder lock 17 which is worked by the key 18. Obviously, the locking element 17 is welded or otherwise securely fixed in the position shown to the top surface of the overall casing 19 which neatly and thoroughly covers the locking and working mechanisms and also the bell portion of the device; the part covering the bell is indicated at 20. The cam arm 15 shifts the finger extension 21 on the stop plate 13 so as to draw inwardly the bolt 6 against the compression spring 55.

The guide 10 and the catch 14 are part of a movable carriage and are joined together as an integral unit by the flat side rails 23 and 24 which neatly and smoothly slide between the elongated guide bars 25 and 26 which are secured to or integral with the base 5. These guide bars are surfaced with a suitable non-rusting metal or other material so that weather conditions will not prevent their proper working. One end of each guide bar has a post 27 to which is attached the middle portion of a coiled spring 28, the ends of which are connected to their respective proximate holding means 29 and 30 on the guide plate and slide rails, as shown, in order to provide a very strong means of constantly urging the entire carriage away from the keeper 4' so as to positively shift the bolt rod and its tongue 6 into the confines of the casing.

The catch element 14 is held in position by an appreciable force, produced by the springs 28 against a stop plate 32 which is secured to the top portion of the boss element 33. When the catch element 14 is raised, the edges 14' and 14'' engage the stop plate 32, but when this catch element is forced downwardly, the edges 14' and 14'' are freed from the fixed stop plate 32 and the central opening of the catch element 14 envelops the boss 33, see Fig. 2.

The portion 33 of the base 5 has a bore or dowel pin receiving opening 34 to accommodate the pin 35 which is integral with the casing, see Fig. 5, which is one of the holding means for anchoring the casing to the base. The bolt side of the device has the screws 8' and 7' which hold the flange of the coverall casing to the threaded bores in the guides 8 and 7, see Fig. 2.

A recessed glass plate 70 is provided directly over the catch element 14, see Fig. 5, and over this glass plate there is a hammer or breaker element 36 which has an integral arm 37 that is pivoted at 38 to a bracket arm means 39 that is integral with the top of the casing 19. When this hammer is struck by any means with sufficient force in the direction indicated by the arrow in Fig. 5, the hammer breaks the glass and forces the catch element 14 downwardly to release it from the stop plate 32 and thus move the carriage so as to withdraw the bolt from the keeper 4'.

The bell mechanism is of any standard make suitable for the purposes and is preferably of the winding type, that is, the bell is rotated in order to wind it. Such a bell device may have the main spring 50 which has one end thereof indicated at 51 fixed to a post and the other end fixed to the winding stem 52 upon which is attached the bell 53.

A large gear 54 is fixed to the stem and this gear is in mesh with a smaller gear 55 through the gear reduction means 56. The gear 55 has in a fixed relationship therewith the escapement wheel 57 which operates the escapement type clapper member 58 for ringing the bell 53. The foregoing elements are well known in the art and no claim is made thereto, that is, the bell structure per se. In order to start and stop the sounding of the bell in a positive manner, a flanged lever 59 is provided which is pivoted to a false bottom 61 at 60, the other end thereof, see Fig. 7 in particular, has a hook-like portion indicated at 62 which passes part way around a post or stud of the gear means 56, as shown; and this distal end also has the turned-up or flanged portion 63 which has a protruded dog 64 which engages the teeth on the gear means

56 and prevents same from rotating when the dog is in downward position.

The lever 59 is sprung downwardly so that the dog 64 always engages the teeth of the gear means 56 until raised. For raising the dog 64, that is, the entire end of the lever 59, a bar 65 is employed and this bar is pivoted at 66 to the base. The bell-end of the bar has a turned-up corner portion or cam-like means 67 which rides smoothly under the lever 59 in a sliding manner and when shifted clockwise as viewed in Fig. 2, forces the lever end 63 upwardly. The other end of this bar 65 has a narrowed and protruded portion 68 that is shifted to the left when struck by the guide plate 10 of the carriage, but shifted to the right when struck by the catch 14 of the carriage, see Fig. 2, thus allowing the bell-clapper 58 to operate only when the guide plate 10 strikes the pivoted bar 65.

From the foregoing, it should now be clear that when the glass 70 is broken by a blow upon the hammer means 36, the catch element 14 is forced downwardly away from its stop 32 and thus releases the carriage mechanism so it will automatically shift and move the levers 65 and 59 so as to release the gear means 56 by displacing the dog means 64.

In the event it is desired to open the lock, that is withdraw the bolt or tongue 6 from its keeper without disturbing the set position of the automatic mechanism, the key 18 is employed to rotate the arm 15 and force the plate 13 to the left as shown in Fig. 5; this plate 13 not disturbing the carriage at all.

It is, of course, understood that various changes and modifications may be made in the details of form, style, design, materials and construction of the whole or any part of the specifically described embodiment of this invention without departing from the spirit thereof in that such changes and modifications are considered as being within the scope of the following claims.

I claim:

1. In an alarm device for emergency doors and the like, a base and a cover therefor defining a housing, operating mechanism in said housing comprising carriage means and a bolt shiftable therewith and independently thereof, a catch element carried by said carriage means, an alarm unit mounted on said base, means interposed between said carriage means and said alarm unit for causing operation of the alarm unit when said catch element is moved in a certain direction, spring means attached to said carriage means and to portions of said base constantly urging said carriage means in a direction to release and operate said alarm unit, a stop element fixed to said base adapted to hold the carriage means in inoperative spring tensioned position, means on said catch element engaging said stop element when said catch element is in a latching position, said housing containing an aperture adjacent said catch element, a frangible element closing said aperture, and external hammer means pivoted to said housing, said hammer means being adapted to break said frangible element, release said catch element, and thereby actuate said alarm unit.

2. In an alarm device for emergency doors and the like, a base and a cover therefor defining a housing, operating mechanism in said housing comprising carriage means and a bolt shiftable therewith and independently thereof, a catch element carried by said carriage means, guides for said carriage fixed to said base, an alarm unit

mounted on said base, means transmitting movement of said catch element in one direction to actuate said alarm unit, spring means attached to said carriage means and to portions of said base constantly urging said catch element in a direction to release and operate said alarm unit, a stop element fixed to said base adapted to hold the catch element in inoperative spring tensioned position, means on the catch element engaging said stop plate when the catch element is in a latching position, said alarm unit having a toothed wheel, a pivoted spring lever in said unit having a dog at one end thereof engaging a tooth on the wheel in its normally lowered position, and a bar pivoted to said base having a cam at one end engageable with said dog to raise said lever and release said toothed wheel, the other end of said bar being located in the line of movement of a portion of said catch element whereby said catch element can shift said bar to release said wheel.

3. In a locking device for closure means, a frame, an alarm mechanism mounted on said frame, a carriage movably supported on said frame, a spring biasing said carriage in one direction relative to said frame, an actuator transmitting movement of said carriage in said direction to operate said alarm mechanism, detent means for restraining movement of said carriage relative to said frame, a bolt movable with said carriage and relative thereto, a spring biasing said bolt in another direction, key actuated means for shifting said bolt independently of said carriage, and cover means protecting said detent against undetected displacement.

4. In a locking device for closure means, a frame, an alarm mechanism mounted on said frame, guide means carried by said frame, a carriage reciprocably supported on said frame for movement relative to said guide means, a spring biasing said carriage in one direction relative to said frame, an actuator transmitting movement of said carriage in said direction to operate said alarm mechanism, detent means for restraining movement of said carriage relative to said frame, a bolt movable with said carriage and relative thereto, a spring biasing said bolt in another direction, key actuated means for shifting said bolt independently of said carriage, and cover means protecting said detent against undetected displacement.

5. In a locking device for closure means, a frame, an alarm mechanism mounted on said frame, a carriage movably supported on said frame, a spring biasing said carriage in one direction relative to said frame, an actuator transmitting movement of said carriage in said direction to operate said alarm mechanism, detent means for restraining movement of said carriage relative to said frame, a bolt movable with said carriage and reciprocable relative thereto, a spring biasing said bolt in another direction, key actuated means for shifting said bolt independently of said carriage, and cover means protecting said detent against undetected displacement.

6. In a locking device for closure means, a frame, an alarm mechanism mounted on said frame, a carriage movably supported on said frame, a spring biasing said carriage in one di-

rection relative to said frame, an actuator transmitting movement of said carriage in said direction to operate said alarm mechanism, detent means secured to said carriage for restraining movement of said carriage relative to said frame, a bolt movable with said carriage and relative thereto, a spring biasing said bolt in another direction, key actuated means for shifting said bolt independently of said carriage, and cover means protecting said detent against undetected displacement.

7. In a locking device for closure means, a frame, a cover defining a housing with said frame, an alarm mechanism mounted on said frame, a carriage movably supported on said frame, a spring biasing said carriage in one direction relative to said frame, an actuator transmitting movement of said carriage in said direction to operate said alarm mechanism, detent means for restraining movement of said carriage relative to said frame, a bolt movable with said carriage and relative thereto, a spring biasing said bolt in another direction, key actuated means for shifting said bolt independently of said carriage, said housing containing an opening registering with said detent and a frangible member covering said opening and protecting said detent against undetected displacement.

8. In a locking device for closure means, a frame, an alarm mechanism mounted on said frame, a carriage movably supported on said frame, a spring biasing said carriage in one direction relative to said frame, an actuator transmitting movement of said carriage in said direction to operate said alarm mechanism, detent means displaceable in a path substantially normal to said direction for restraining movement of said carriage relative to said frame, a bolt movable with said carriage and relative thereto, a spring biasing said bolt in another direction, key actuated means for shifting said bolt independently of said carriage, and cover means protecting said detent against undetected displacement.

9. In a locking device for closure means, a housing including a frame, an alarm mechanism mounted on said frame, a carriage movably supported on said frame, a spring biasing said carriage in one direction relative to said frame, an actuator transmitting movement of said carriage in said direction to operate said alarm mechanism, detent means for restraining movement of said carriage relative to said frame, a bolt movable with said carriage and relative thereto, a spring biasing said bolt in another direction, key actuated means for shifting said bolt independently of said carriage, a destructible cover carried by said housing protecting said detent against undetected displacement, and means carried externally of said housing for destroying said cover.
